ROBERT L. DAVIS, OF PITTSBURGH, AND JOHN P. STAKEL, OF EDGEWOOD, PENNSYLVANIA, ASSIGNORS TO WESTINGHOUSE ELECTRIC AND MANUFACTURING COMPANY, A CORPORATION OF PENNSYLVANIA

INDUCTOR

Application filed April 29, 1927. Serial No. 187,468.

Our invention relates to inductors and particularly to inductors suitable for use with radio-frequency apparatus such as radio transmitting systems, radio-frequency amplifying systems and the like.

An object of our invention is to provide improved inductance devices in which the energy losses are a minimum.

Another object of our invention is to produce an inductance device adapted for the ready dissipation of heat produced therein by energy losses.

Another object of our invention is to produce a highly insulated low-loss inductance device particularly adapted for use in apparatus handling alternating currents at frequencies above 1,000 kilocycles.

Another object of our invention is to provide an inductance device which shall be capable of being quickly modified to accommodate either ribbon-like conductors or conductors having substantially circular cross-section.

Another object of our invention is to provide an inductance device capable of carrying large currents at high-voltage radio-frequencies.

A still further and more specific object of our invention is to provide, for use in connection with an inductance device, conductor-supporting elements that may be easily adapted for inductors having widely differing inductance values.

In the construction of inductance devices adapted to be used in apparatus which is arranged to handle currents at radio frequencies, numerous difficulties have previously been experienced. The energy losses caused by electrostatic and electromagnetic hysteresis effects increase very rapidly with increase in frequency, and difficulty has been experienced in constructing inductors capable of handling large currents of electrical energy at the frequencies corresponding to short electromagnetic wave lengths.

The difficulties seem to increase very markedly at frequencies of 1500 kilocycles or higher, the principal losses at such frequencies being occasioned by the generation

of heat in the structures which carry the wire, conducting tube, or strap employed.

It has been found that the usual insulating materials, such as bakelite, micarta, etc., have such high electrostatic and electromagnetic losses that at the higher frequencies a prohibitive amount of energy is wasted in them, causing heating which not infrequently seriously damages the apparatus.

Many of the difficulties hitherto experienced have been solved by the invention covered by application, Serial No. 5,049, filed in the name of Frank Conrad. As disclosed in that application, an improved inductance device comprises a frame work of wood which has been carefully dried and covered with a suitable surface-sealing and insulating covering. Upon this wooden frame work are mounted a plurality of insulating members parallel to an axis thereof. These members are preferably formed of molded, heat-resisting glass such as pyrex, and are preferably rectangular in shape.

According to the application referred to, these insulator members are provided with a plurality of spaced projections upon one edge adapted to space apart the successive turns of a conductor. The insulating members are preferably removably mounted upon the wooden frame work referred to and are held in position by the tension exerted upon the conductor when it is wound thereon.

We have found, however, that in order to provide for a plurality of inductors of widely differing inductance values, it was necessary to maintain a very large supply of the insulating pyrex strips referred to. This extra supply necessitates an outlay of money, which is unduly large.

We have also found that the insulator strips did not provide means for readily attaching the otherwise free ends of the conductor in order to maintain them firmly in position.

Accordingly, by the present invention, we have provided conductor-supporting elements which are readily adapted to be used with inductance devices having widely different inductance values, and have further so modified the insulating strips that an end

of the conductor may be firmly attached thereto with minimum effort and with assurance that it will not work loose. Specifically, our invention contemplates providing the insulating strips with a plurality of spaced projections upon each of the edges thereof, the projections on one of the edges being spaced further apart than the projections upon the opposite edge. Each separate pyrex, or glass, strip is thus given a double measure of utility, inasmuch as it may be utilized as a component part in the assembly of inductors having widely different inductance values.

15 In addition, we have modified the ends of the insulating members by providing a notch therein intermediate of the serrated edges thereof. The free end of the wire, tube, or strap, may be wrapped around one of the 20 branches of the notch referred to and may be securely anchored in position.

Among the novel features of our invention are those particularly set forth in the appended claim. The invention in its entirety, however, as well as further objects and advantages thereof, will best be understood by reference to the following description of certain specific embodiments taken in connection with the accompanying drawings, 30 in which,

Figure 1 is a side elevational view of an inductance device equipped with a preferred embodiment of our invention,

Figs. 2 and 3 are side and end elevational views, respectively, of a form of our invention adapted to support strap, or ribbon, conductors.

Figs. 4 and 5 are side and end elevational views, respectively, of a form of invention 40 adapted to support a solid conductor, and

Figs. 6 and 7 are side and end elevational views, respectively, of a form of our invention particularly adapted to the support of a tube, or pipe, conductor having a large 45 diameter.

Referring to Fig. 1, a set of rings 1, 2 and 3 have attached thereto a plurality of grooved cross pieces 4. A pair of supporting members 5 are respectively attached to the end 50 rings 1 and 3. As explained in the copending application of Conrad previously referred to, all of these members are preferably made of wood and are given a special drying and insulating treatment before assembly.

55 A plurality of insulating members 6 are mounted in the grooves of the cross pieces 4 and extend parallel to an axis passing through the annular rings. Each of the insulating members 6 is provided with a plurality of spaced projections 7 upon the edge opposite the edge in contact with the grooved cross pieces 4. The edge carrying the projections is preferably slightly convex and is provided with rounded corners.

60 These insulating pieces preferably fit the

grooves quite closely in order that the form may be handled without danger, even though the conductor has not been wound around it.

A ribbon, or strap, conductor 8 is wound around the insulating members 6, successive members being shifted axially a slight amount in order to provide for the necessary pitch.

70 Thus far, the device described is substantially the same as that disclosed in the Conrad application referred to. We have provided, however, as before explained, an additional series of spaced projections 9 upon the edges of the members 6 which, in Fig. 1, are shown in contact with the grooved cross 75 pieces 4. These extra sets of projections are, as shown, closer together than the projections which accommodate the strap conductor.

80 Each end of the insulating members 6 is provided with a notch 11, having branches 12 and 13, which provides means for securely anchoring the ends of the conductor as shown in Figs. 3, 5 and 7.

85 By winding a flat conductor having a width 90 equal to the space between the projections, successively around the insulating members until all of the spaces have been occupied and the wire securely anchored, an inductor may be provided having an accurately predetermined inductance value. If, for any reason, it is desired to change the inductance value, the conductor may be removed, all of the insulating members reversed, and a second conductor having a width equal to the spaces 95 between the projections now uppermost may be wound around the elements and anchored in the manner just described. It is also possible to accurately predetermine, within a small percentage of error, the inductance 100 value of the second inductor.

105 The principal advantage of our invention lies in the fact that a large number of differing inductance devices may be constructed by utilizing the same fixed wooden form and by making use of but a small number of differing insulating strips. When the insulating strips are constructed according to our invention it is possible to reduce the replacement stock of insulators necessary to be kept 110 on hand by 50%, at least, if not more.

115 The provision of the anchoring notch 11 permits the inductor to be assembled much more rigidly than if the ends of the conductor are merely wrapped around the unnotched ends of the insulator strips, as shown in the Conrad application previously referred to.

120 Although we have shown but three embodiments of our invention in the accompanying drawings, many modifications thereof will be apparent to those skilled in the art. Our invention, therefore, is to be limited only by the prior art and by the spirit of the appended claim.

We claim as our invention:

A coil supporting device comprising a frame, and a plurality of elongated approximately rectangular insulating elements ⁵ movably supported thereby in circumferential spaced relation, an exposed edge of each of said elements being provided with a series of convolution-separating projections, another edge of each of said elements being provided with a plurality of convolution-separating projections differently spaced from the projections on said exposed edge, whereby upon reversal of said elements relative to said frame a conductor may be wound about said ¹⁰ elements to constitute a coil having a value of inductance different from that of a coil formed by winding an inductor around said elements before their reversal.

In testimony whereof, we have hereunto ²⁰ subscribed our names this 25th day of April, 1927.

ROBERT L. DAVIS.
JOHN P. STAKEL.
